UNITED STATES PATENT OFFICE.

CHARLES M. BLANCHARD, OF ELYRIA, OHIO.

INTERNAL-COMBUSTION ENGINE.

1,124,837.

Specification of Letters Patent.

Patented Jan. 12, 1915.

Application filed July 25, 1912. Serial No. 711,464.

To all whom it may concern:

Be it known that I, CHARLES M. BLANCHARD, a citizen of the United States, residing at Elyria, in the county of Lorain and State 5 of Ohio, have invented a certain new and useful Improvement in Internal-Combustion Engines, of which the following is a full, clear, and exact description, reference being had to the accompanying drawings.

10 This invention relates to an internal combustion engine of the two-cycle type, the primary object being to provide an efficient form of such type of engine in which the fuel is burned under constant pressure. The 15 two-cycle constant pressure operation gives a power impulse every stroke, and a low maximum pressure but high mean effective pressure, with the result that the construction may be lighter and cheaper than in a 20 four-cycle engine or a constant volume or an explosion engine. In my engine, air is compressed in the cylinder by the return stroke of the piston, and, at or near the dead center, oil is atomized under pressure into this 25 highly compressed air; and ignites from the heat of such air assisted by hot heads on the cylinder and piston which have retained heat from the previous combustion stroke. The 30 continuance of the admission during a portion of the outward stroke gives a constant pressure until the cut off, when expansion takes place until the exhaust at the end of the outward stroke. The pressure cycle is accordingly similar to that of a steam engine. 35 My engine is adapted for operation by various heavy, cheap oils, whereby great power is attained at low cost. The engine is uniform in operation and automatic in its control, and readily adjusted to meet various 40 conditions, and its parts easily accessible for cleaning or repair.

The invention includes the means by which I obtain the various features mentioned, and also other minor features, contributing to 45 the efficiency and economy of operation, as well as the durability of the engine.

A preferred form of my invention is illustrated in the drawings hereof and is herein-after fully described.

50 In the drawings, Figure 1 is a side elevation of a horizontal engine embodying my invention, looking at what may be termed the working side of the engine; Fig. 2 is a side elevation looking from the same side,

and sectioned on a vertical plane through the 55 valve chest; Fig. 3 is a horizontal section through the main cylinders and the valve chest, as indicated by the offset line 3—3 of Fig. 4; Fig. 4 is a vertical transverse section through the pumping cylinder and 60 valve chest, as indicated by the line 4—4 on Fig. 3; Fig. 5 is an enlarged vertical longitudinal section through the working cylinder of the engine; Figs. 6, 7 and 8 are details of the cam mechanism for controlling 65 the admission valve,—Fig. 6 being a side elevation, Fig. 7 an end view, and Fig. 8 a development of the surface of the cam.

As shown in the drawings, 10 represents that portion of the engine frame in which is 70 journaled the main shaft, and 11 indicates the main cylinder, which is suitably bolted at 12 to the frame 10, and is supported by an independent casting 14. I will first describe the construction of the main cylinder 75 and its piston, as illustrated in Fig. 5.

As shown in Fig. 5, the main cylinder has an enlarged bore 20, leading from the crank end of the cylinder, and adjacent to the head end of the cylinder is a reduced bore 21. 80 Slidable in the enlarged bore is a pumping piston 22 and slidable in the reduced bore is the driving piston 23, these two pistons being bolted together by bolts 24 accessible from the crank end. The piston 23 is preferably hollow, as shown, and has an opening 85 25 at its outer end communicating with an opening 26 in the adjacent end of the piston 22. One of the pistons (the piston 22, as shown) carries a suitable wrist pin 27 on 90 which is journaled the inner end of the connecting rod 28. This connects with a crank (not shown) on the main crank shaft 29 carried by the frame 10.

On the head end of the piston 23 is a false 95 head 30, which is shown as secured by a cap screw 31 accessible through the opening 25 in the other end of the piston. 35 indicates the head of the main cylinder, this head being suitably bolted to the cylinder wall. 100 This unjacketed cylinder head and the false head on the piston become and remain very hot. At the end of the outward stroke air is admitted to the cylinder 21 through the port 18 from a passageway 19 in constant 105 communication with a low pressure air tank supplied by the pumping piston 22. This incoming air is directed toward the head end

of the cylinder by the slope of the false head 30 and is compressed by the returning piston. At the dead center oil is atomized under pressure into the air compressed in the space between the hot cylinder head 35 and the hot false head 30, and igniting, forces the piston to the right (Fig. 5) thereby driving the engine. 37, in Fig. 5, illustrates the admission port for the fuel which is open for a definite portion of the working stroke, being controlled by a valve, to be hereinafter described. At the end of the outward stroke of the piston the gases escape through the port 40 and the passageway 41 in the base 14 into the main exhaust pipe 42, at the same time that fresh air enters through the port 18.

The space between the inner wall 21 for the main cylinder and the outer wall 11 provides a suitable water jacket, designated 43, this jacket having an intake at 44 and an exit at 45. In the form shown, the outer wall of the jacket is a continuation of the wall of the pump cylinder 11. At the head end of the cylinder is a suitable cap 46, secured by a bolt 46 on the cylinder head. This is to protect the operator from coming into contact with the hot cylinder head, and also to provide a confined air insulating space about the outer face of the head.

The piston 22 performs the double duty of giving the initial compression to the air and of acting as a cross head for the main piston 23 and the connecting rod 28. Air is admitted to the space 50 at the head of the piston 22 and after being compressed in such space is discharged into a tank which is in open communication with the passageway 19. The valve which coöperates with the piston 22 to make the low pressure pump is shown in Figs. 2, 3 and 4, and will now be described.

15, in Figs. 1 to 4, indicates a suitable casting bolted onto the side of the cylinder casting 11 and carrying the cylinders and jackets for the low pressure air valve and for the second and third stage air pumps used for raising the air to atomize the oil as hereinafter described. Set into this casting is a suitable sleeve 52 which constitutes the cylinder of the low pressure air valve and the second stage air pump. The annular space 50 at the head of the piston 22 receives air by the piston's outward stroke 45 through a passageway 51, and on the inward stroke discharges such air, compressed, through the same passageway. This passageway 51 communicates by ports 53 with the interior of the valve cylinder 52. Operating in the valve cylinder 52 is the valve for the low pressure air comprising the pistons 55 and 56 and the intermediate connection 57. This valve is driven by the crank shaft 29. As shown, there is a 60 wrist pin 39 suitably supported in the in-

terior of the piston 55, and on this pin is journaled the eccentric rod 60 carrying at its other end a strap extending around the eccentric 61 on the main crank shaft 29. Accordingly, the pistons 55 and 56 are reciprocated in correspondence with the piston 22.

63 indicates a suitable pipe connecting with the outer air for supplying air to the first-stage pump 22, and 64 indicates a pipe 75 for carrying this air, when somewhat compressed, to the low pressure tank 65. These two pipes 63 and 64 communicate with the cylinder 52 through ports 57 and 58. The pipe 64 also communicates with the main cylinder 21 by the passageway 19 and port 18 heretofore referred to.

It will be seen that, as the driving piston is starting on its outward stroke, the movement of the eccentric forces the valve piston 56 to cover the port 58 and the piston 55 to uncover the port 57, whereby the space 50 is in communication with the outer air and air is drawn into the cylinder 20. Then, when the driving piston is on its inner stroke, the eccentric has shifted the pistons 55 and 56 to the right so that the ports 57 are closed and the ports 58 are open, and thus the air compressed in the space 50 is forced under pressure out through the pipe 64 into the tank 65. By this means I obtain air of a few pounds pressure (say six pounds) in the tank 65 for use in the main cylinder. I prefer to take some of this air also for raising to a higher pressure to atomize the oil. Such high pressure air is raised by two stages, as will now be described.

70 indicates the piston of the second-stage air pump. This piston is formed on the forward or right hand end of the valve piston 56. It operates to draw in air from the tank 65 through the pipe 66 and the choke valve 67 (to be hereinafter described) and pipe 68 and to discharge it through the pipe 72 into a tank 73. 69 and 71 indicate suitable check valves for controlling the admission of air to the pump space 75 and its exit therefrom.

I use the air from the tank 73 for several purposes. A portion of it passes through a governing valve to the third stage pump for producing the highest pressure air for atomizing the fuel; a portion passes to the liquid fuel reservoir for forcing it to the fuel pump, and air is also taken from this tank directly into the cylinder, as hereinafter explained, for starting the engine. To insure against damage to any of the reservoirs by excessive pressure, as well as to produce a regular feed of the fuel, it is desirable to maintain the air in the tank 73 at a substantially constant pressure, say, for example, one hundred and fifty pounds. I accomplish this by provid-

ing the choke valve 67 referred to, which is under the influence of the air in the tank 73 and is so arranged that it shuts off the communication between the pipes 66 and 68 whenever the air pressure in the tank 73 exceeds a predetermined minimum, opening such passageway when the air pressure drops below this minimum.

Fig. 9 shows a simple and effective form of the choke valve. As will be seen from this figure, there is a passageway 76 through the casing 67 adapted to connect the pipes 66 and 68. This passageway is under the control of a piston 77 carried normally 15 away from the opening by the spring 78 which extends within the casing and is compressed by a cap 79 screwing into the end of the casing 67. The piston 77 is connected with a small piston 80 sliding in a cylinder 20 81 extended from the casing 67. 82 indicates a pipe forming communication between this cylinder 81 and the tank 73. The spring 78 is so adjusted that when the tank pressure is up to the desired amount, the 25 air pressure in the pipe 82 acting on the piston 80, forces the piston 77 to close the passageway 76 until the air pressure in the tank is reduced. When the passageway 76 is closed the second stage pump receives no 30 air and none is pumped to the tank 73.

85, in Fig. 2, indicates the third stage air pump. This is formed on the head end of the piston 70 and occupies a cylinder formed within the same casting 15. 84 indicates a pipe supplied by air from the tank 73, after passing through a governing valve to be hereinafter described, and thus air under considerable pressure passes to the space 87 at the head of the piston 85 40 through a check valve 88. The air is compressed in this space 87 and discharged past a check valve 89 into the high pressure pipe 90, which leads to the admission valve. This high pressure air, which atomizes the 45 oil at the admission valve may conveniently have a pressure of five or six hundred pounds.

I will now describe the governor which controls the atomizing air and also the fuel 50 supply, governor shown being of the type known in the trade as a "Rites governor."

92, in Fig. 1, illustrates the weighted bar of the governor, which is pivotally connected at 93 to one of the fly wheels 94. A 55 spring 95 tends to advance this governor with the rotating fly wheel until it is stopped by a suitable abutment 96. The inertia, however, of the governor tends to make it lag during the rotation of the fly wheel until it strikes the rear abutment 97. The 60 governor bar is thus held in equilibrium between these two tendencies, so that, when the speed of rotation increases, the governor bar moves relatively forward, and 65 vice versa.

100 indicates a connecting rod, one end of which is strapped around a pin 101 on the governor bar. In the position shown in Fig. 1, the pin 101 is at the left of the axis of the crank shaft so that this pin acts as 70 an eccentric and gives a reciprocating movement to the connecting rod 100. The amount of this reciprocation varies with the speed of rotation of the fly wheel, due to the independent movement of the governor bar. The rod 100 is connected at the right hand by an adjustable connection with a rock arm 105 which is on the rock shaft 106. Another arm 107 (Fig. 3) on this shaft connects with the rod 108. This rod 108 is 75 connected at its forward end with a sliding block or cross head 110 sliding in a cylindrical guideway provided by a bracket 16 bolted to the side of the casting 15. This bracket 16 carries also a pump casing 112, 80 in which rides a plunger 113 sliding through a suitable stuffing box 114 and connected with the cross head 110. This plunger rod 113 acts as a pump for the fuel, receiving this fuel from a pipe 117 and discharging 90 it into a pipe 118 which leads to the admission valve of the engine. Suitable check valves 119 and 120 are contained in these pipes to make an effective pump.

I have shown two supply pipes communicating with the pipe 117; namely, a pipe 121 under the control of the valve 123 for heavier oil, and a pipe 122 under the control of a similar valve 124 for gasoline. The gasoline is used in starting the engine 100 and thereafter shut off and the oil used, the same pump serving for either fuel. It is to be understood that the oils and gasoline are forced to the valves 123 and 124 by air pressure in their respective tanks, this air, if 105 desired, coming from the tank 73.

Connecting with the rod 108, for simultaneous operation with the fuel pump, is a controller valve for the atomizing air heretofore referred to. This valve consists 110 of a casing 130, a rod 131 reciprocable therein, and connected by a bracket arm 133 with the cross head 110 above mentioned. The high pressure air pipe 135 from the tank 73 is connected with the chamber in 115 the casing 130, and from this chamber leads the pipe 84 to the third stage air pumps 85, heretofore described. When the shifting of the governor shifts the rod 108 to reduce the amount of oil pumped, it also shifts the 120 rod 131 to reduce the amount of air admitted beyond the end of the rod in the chamber leading to the pipe 84; and, conversely, an increase in the amount of oil pumped results also in an increase in the amount of 125 air supplies. Suitable nuts 134 on the rod 131 enable a proper adjustment of this air controlling valve.

The stroke of the fuel pump and air valve above described may be regulated by turn- 130

ing the knob 102 (Fig. 1) which is on a screw 113 extending freely through the rod shaft 106 and occupying a slot in the arm 105. A nut on this screw, guided by such slot, carries the pin 104 to which the governor rod 100 is connected. This connection is by means of a member 109 journaled on the pin 104 and having a sleeve into which the rod 100 extends. A pin with a 5 knob 111 normally locks the rod 100 in the sleeve. Accordingly, by turning the knob 102 one may regulate the amount of fuel and air delivered; while by drawing up the knob 111 the pump and air valve may be 10 rendered idle, and thus the engine stopped. Of course, the engine may be stopped by closing the fuel valves 123 and 124.

It will be seen from the above description that air and oil under pressure and in regulated quantity, are periodically admitted 20 through the pipes 90 and 118 to the main admission valve, the amount of the oil and air being under the control of the speed governor. The admission valve is directly 25 and positively connected with the crank shaft so that it is operated in direct correspondence with the travel of the piston.

I will now describe the admission valve 30 and its operation, reference being had to Figs. 1, 2 and 5 to 8 inclusive. Referring first to Fig. 5, the numeral 37 indicates the fuel admission port and, as heretofore stated, 118 the oil pipe and 90 the high pressure air pipe. These two pipes discharge 35 into an annular chamber 140 in a suitable tubular casing 141 set into the body of the cylinder wall. In the chamber 140 is a valve rod 142, slideable through a plug 143, and adapted to coöperate with a seat just 40 above the port 37. The outer surface of the plug 143 is knurled or roughened so that the oil and air, in passing down the outer side of the plug to the cylinder are thoroughly mixed and incorporated. It is to 45 be understood that when the rod 142 is raised, the fuel port 37 is opened and the high pressure air atomizes the oil into the compressed air in the cylinder, and the highly heated mixture immediately ignites, 50 the combustion continuing at a constant pressure as long as the port 37 is open.

The rod 142 is secured at its upper end to a head 144 which is slideable in a housing in the casing 146 secured to a bracket 147 55 on the top of the main cylinder. Above the head 144 is a compression spring 148 which extends into and is adjusted by the cap 149 which screws downwardly within the housing mentioned. The head 144 is extended 60 downwardly about the rod 142 and rests on a cross bar 150 of the bifurcated lever 152. This lever is pivoted at 153 to the bracket 147. The other end of the lever carries, between its arms, a roller 155 which rests on 65 and coacts with a rocking cam 160. The

roller is pressed toward the cam by a spring 157 bearing downward on a sliding head 158 in a second housing in the casing 146, the spring being compressed by the screw cap 159.

It will be seen from the above description 70 that the spring 148 tends to maintain the valve 142 on its seat, and does so maintain it except when lifted by the arm 152. The spring 157 tends to hold the arm with the admission valve closed and the roller 155 pressing on the cam, but when the hump 161 on the cam raises the roller and arm upwardly, such movement raises the admission valve and allows the charge to enter the cylinder. 75

The cam 160 is secured on a rock shaft 162, which is journaled in a suitable disk-like frame bracket 163. On the other end of the rock shaft is a rock arm 164 (Figs. 85 1 and 2) which is connected by a link 165 with the rock arm 166. This arm is on a shaft 168 which carries an opposite arm 169 which is connected by a link 167 with the wrist pin 59 on which the eccentric rod 60 90 is journaled. Accordingly, the reciprocation of the eccentric rod reciprocates the rod 165 and thus rocks the cam 160. The cam is peculiarly formed, so that when rocking in one direction, it does not elevate the roller 95 155 but, when rocking in the other direction does elevate the roller. This causes the fuel admission valve to be open once only for the outgoing and return stroke of the piston. 100

I accomplish this peculiar alternate operation of the cam above mentioned by making the roller 155 laterally shiftable on the pin 156 carried by the arm 152 so that the hump 161 on one stroke strikes the roller 105 and on the opposite stroke misses it. I provide two side cams on the cam 160 to effect this shifting of the roller. This is illustrated in Figs. 6, 7 and 8. On either side of the intermediate portion 155 of the roller 110 are two disks 170 and 171 which are designed to coact with the edges of the cam, and near the opposite ends of these edges are two oppositely formed cams 173 and 174. When the cam 173 engages the disk 115 171 it draws the roller toward the right in Fig. 7, so that it is out of the path of the projection 161. This draws the disk 170 over against the opposite side of the cam, so that, when the cam edge 174 engages the disk 170 it draws the roller back into position so that the intermediate roller 155 is 120 positioned to be engaged by the hump 161, as shown in Fig. 7.

In the embodiment shown in the drawings, the main eccentric 61 is so set that, as the main piston 23 is about reaching the head position on the return stroke, the cam is moving in a direction from the head of the cylinder toward the crank and thus the 125 130

hump 161 passes under the roller 155 and raises the admission valve while the piston is on the dead center, and holds the valve open during perhaps one tenth of the outward stroke of the piston. Now, as the cam continues to rock in this direction, the cam edge 173 engaging the disk 171 draws the roller into position to miss the projection 161, and then the eccentric rocks the cam 10 in the opposite direction and carries that projection idly past the roller. As the cam is reaching the limit of its movement in this direction the edge 174 engages the disk 170 and draws back the roller to normal position 15 so that it is in the path of the hump 161.

The actual time which the admission valve is open may be regulated with reference to the piston position by turning the rod 165, which has at its ends right and left hand 20 threads which engage in corresponding sockets connecting with the arms 164 and 166. A suitable knurled hand-hold 177 on the rod 165 furnishes convenient means for turning it. A suitable mark, indicated 178, 25 on the frame bracket 163 may form a simple guide for resetting the cam in its normal position.

The engine may be conveniently started by compressed air from the high pressure 30 tank 73. To provide for this I mount a bonnet 180 (Figs. 3 and 4) on the main cylinder, this bonnet having a bore communicating with the combustion space by a passage-way 181. A check valve 182 prevents outward movement of fluid in the bore. A pipe 183 connects this bonnet beyond the check valve with the tank 73 under the control of a suitable valve (not shown) which may be operated by a cam on the main shaft 29, 35 such cam being properly positioned with reference to the crank to open the air pipe in proper time. After the engine is running under its own power, the air pipe 183 is shut off. 185, in Fig. 3, indicates a pop 40 safety valve, which is shown as mounted on the bonnet 180. 186 indicates a suitable cock connected with this bonnet, by which an indicator, for example, may be put in communication with the cylinder. After 45 the engine has been started by air pressure, it is desirable to start the motive power operation with gasolene, or other light hydro-carbon, which may be admitted to the fuel pump by the valve 124, as I have heretofore explained. I provide a suitable jump spark 50 for igniting such light hydro-carbon. The spark plug may be placed in any suitable position in the combustion space in the cylinder. It is illustrated at 190 in Fig. 5. 55 Fig. 1 illustrates, at 192, the head of the spark plug, and, at 191, the sparking wires. 60 It will be seen from the above description that I have provided a very compact two-cycle constant pressure oil engine designed, 65 after starting, to raise its own air pressure

and utilize the same in conjunction with heavy hydro-carbon oil. By the maintenance of air under a comparatively high pressure in the tank, I am enabled to start the engine quickly, and to pass, in a very 70 few minutes, from the air starting or the gasolene operation, to a normal running of the engine. In such normal running, the low pressure air scavenges the cylinder and supplies the air for the combustion, which 75 takes place without excessive pressure.

Another feature of my engine on which comment should be made is the utilization of various pistons, etc., for forming cross heads for the connected parts. Thus, the 80 low pressure pump piston forms a cross head for the main connecting rod, while the piston 55 of the low pressure air valve forms a cross head for the eccentric rod 60. I have also carried out the cross head construction by the sliding block 110 of the fuel pump and the head 144 for the fuel admission valve.

The accessibility of the parts of this engine is also a valuable feature. The pistons 90 22 and 23 may be taken out through the open crank end of the cylinder 11. The bolts 24 enable the separation of the two pistons; the cap screw 31 enables the removal of the false head 30; the nut on the 95 bolt 47 enables the removal of the protecting cap 46, and the cylinder head 35 may then be removed by removing its bolts. The admission valve and its operating rod are mounted in a removable plug. The 100 check valves for the middle stage air and higher pressure air are contained in removable bonnets suitably bolted on the casting 15.

Comment may also be made on the oiling 105 system of the engine, suitable openings being provided to enable oil to be forced, under pressure, through pipes not shown, to the proper surfaces. Thus, an opening 49 through the casing in the main cylinder, 110 supplies oil to the main piston; an oil opening 13 through the cylinder 11 supplies oil to the piston 22, and a drip pipe 180 supplies oil from this piston to the wrist bearing 27. Oil openings through the casting 115 15 supply oil for the pistons 55, 56 and 85.

It will be seen that my engine embodies numerous features contributing to the efficiency of the operation, as above described. Though the details of such features are 120 comprised within my general invention covered herein, I do not wish to be limited to such particular details further than the state of the prior art and the claims appended hereto require.

It should be noted that the piston construction herein shown is claimed in my application No. 743,451, filed Jan. 22, 1913; also, that the mechanism for operating the admission valve, including the peculiar cam 130

and shifting roller herein described, is claimed in my divisional application No. 743,450, filed January 22, 1913.

Having thus described my invention, what

5 I claim is:

1. In an internal combustion engine, the combination of a main cylinder, a driving piston therein, a pump cylinder, an air pumping piston therein connected with the 10 driving piston, a reciprocating valve for controlling the air to and from said air pumping piston, an air compressing piston mounted on the forward end of the air valve, and conduits for air leading from 15 said air valve to the main cylinder and to the space in front of the air compressing piston mounted on the valve.
2. In an internal combustion engine, the combination, with a driving piston, of an air 20 pumping piston connected therewith, a reciprocating valve for controlling the air to and from said last mentioned piston, a low-pressure air tank, a conduit from the valve to the tank, an air compressing piston 25 mounted on said valve, a conduit from the tank to the space in front of such last mentioned piston, a conduit from such space, and check valves for the last mentioned two conduits.
3. In an internal combustion engine, the combination, with a main piston, of a pumping piston connected therewith, a low pressure air tank into which such pump may 35 discharge, a second stage pump for raising the pressure of some of the air from said tank, a high pressure tank for the air so raised, and a choke valve in the conduit from the low pressure tank to the pump controlled by the air pressure in the high 40 pressure tank.
4. In an internal combustion engine, the combination of a driving piston, a pumping piston connected therewith, an air valve for controlling the air delivered by the 45 pumping piston, a tank into which such air discharges, a pump connected with the air valve for raising the pressure of a portion of the air from such tank, there being a conduit from the tank to the pump, a high pressure air tank, a conduit from the pump to the last mentioned tank, and a choke valve in the conduit from the low pressure tank to the pump, controlled by the air pressure in the high pressure tank.
5. The combination, with a main cylinder, 55 of a driving piston, an air pumping piston connected therewith, an air valve therefor, a second stage pumping piston, a third stage pumping piston mounted on the second stage piston, an air conduit leading from the first mentioned air pump to said valve, a low pressure air tank, conduits from the valve to the main cylinder and such low-pressure tank and from the tank to the second stage pump, a reservoir for high pres- 60 65

sure air, and conduits between it and the second stage pump and third stage pump respectively.

6. The combination, with a driving piston, a pumping piston connected therewith, 70 a piston valve, a second stage pumping piston mounted on said valve, a third stage pumping piston mounted on the second stage piston, an air conduit leading successively from the first mentioned pump to said valve 75 and from the valve to the second stage pump, reservoirs for low pressure air and high pressure air in said conduit between the primary pump and second stage pump and between the second stage pump and third 80 stage pump respectively, a choke valve between the low pressure reservoir and the second stage pump, the choke valve being controlled by the pressure in the high pressure reservoir, and a passageway for low pressure scavenging air to the main cylinder.

7. In an internal combustion engine, the combination, with the driving piston and the low pressure air pump, of a piston valve 90 comprising two connected pistons for controlling the low pressure air, an operating rod for said valve having a wrist pin connection within one of the pistons of the valve, and two air compressing pistons 95 mounted on the opposite end of said piston valve.

8. In an internal combustion engine, the combination, with the cylinder, the driving piston and the low-pressure air pump, of a 100 piston valve comprising two connected pistons for controlling the low pressure air, an operating rod for said valve having a wrist pin connection within one of the pistons of the valve, an air compressing piston 105 mounted on the opposite end of said piston valve, and a high pressure air piston on the forward end of the piston last mentioned, a conduit for air from the air valve to the piston mounted thereon and from that piston to the high pressure piston and from the high pressure piston to the cylinder, and check valves enabling the last mentioned two pistons to act as air pumps to raise the air pressure.

9. In an internal combustion engine, the combination of a main cylinder, piston, connecting rod and crank shaft, a pump piston mounted on the main cylinder, a second pump piston for raising the pressure of air 120 compressed by the first mentioned pump, a third pump piston carried by the second pump piston for again raising the pressure of air compressed by the second pump piston, and means operated by the crank shaft 125 for reciprocating the two last mentioned pump pistons.

10. In an internal combustion engine, the combination of a main cylinder, a piston, connecting rod and crank shaft, a pump 130

piston connected with the main piston, a second pump piston driven by the crank shaft for raising the pressure of air compressed by the first mentioned pump piston, a high pressure air tank to receive air from such pump, a conduit leading from the high pressure tank to the main cylinder, a third pump piston for raising the pressure of air passing through said conduit, rigid with the second named pump piston, and means connecting the two last mentioned pump pistons with the crank shaft.

In testimony whereof, I hereunto affix my signature in the presence of two witnesses.

CHARLES M. BLANCHARD.
